Specification of Letters Patent. Patented Nov. 15, 1921.

Application filed March 4, 1919. Serial No. 280,847.

To all whom it may concern:

Be it known that I, CHARLES G. TIEFEL, a citizen of the United States of America, and a resident of the city of Rochester, in the county of Monroe and State of New York, have invented certain new and useful Improvements in Check-Writers; and I hereby declare the following to be a full, clear, and exact description of the same.

10 This invention relates to printing machines, particularly to machines for printing upon checks or other commercial instruments the amount for which the instrument is to be drawn, and it has for its special object to provide a machine employing a type carrier of novel construction and adapted for printing a series of words designating a monetary amount in a line in such a manner as to render the line readily legible and also 15 to make alteration or substitution of one or more words by others indicating a different amount extremely difficult and capable of ready detection.

A further object is to provide a type carrier by which the words of an amount are printed in such a manner that it is impossible to change one word to another by a subsequent impression of another word on the type carrier, in which the letters appear 20 in the same order as in the first word.

Other advantages will appear in the following description in which reference is had to the accompanying drawings which show a machine embodying the invention.

25 In the drawings:

Figure 1 is a top plan view.

Fig. 2 is a vertical section on the line 2—2 of Fig. 1.

Fig. 3 is a similar view just inside the 30 casing at the right hand end of the machine.

Fig. 4 is a detail sectional view on the line 4—4 of Fig. 3.

Fig. 5 is a similar view on the line 5—5 of 35 Fig. 3.

Fig. 6 is a similar view on the line 6—6 of Fig. 3.

Fig. 7 is a detail view of a portion of the 40 face of a type wheel.

Fig. 8 shows a check having on its face a series of words designating a monetary amount applied by a machine embodying 45 the invention.

The machine shown in the accompanying 50 drawing is constructed to print in full and

in words any desired monetary value, within certain limits, at a single impression. It comprises a set of type carriers, each provided with a line of type for printing each of the various words employed in writing amounts, and so constructed that when the imprint is made there will be no spaces or gaps between the words. The type in each line are graduated in height from one end to the other, thereby making it possible for the eye to grasp the printed words as units as readily as though they were spaced apart while at the same time making it more difficult to change an imprint, either by partially erasing and then printing a different word or by inserting a letter or part of a letter at the end of a word already printed. In the embodiment shown the letters of each word decrease uniformly in height from beginning to end so that lines A (Fig. 8) bounding the upper and lower ends of the letters gradually converge toward the end of the word while the lower line is horizontal.

In the drawings the casing 1 of the machine carries a cross shaft 2 upon which are 50 loosely mounted in contiguity a series of type wheels 3. The casing is slotted at 4 to permit a check or other paper to be inserted beneath the latter and above a platen 5 co-operating with the type wheels, the platen 55 being carried on lever arms 6 pivoted on a shaft 7 extending across the rear of the casing.

In the embodiment shown the type wheels are of similar construction and are all of 60 the same width face, each wheel having words arranged in rows 8 on its cylindrical periphery. All of the words required in an amount may appear on each type wheel, and the words preferably extend the full width 65 of the faces of the wheels regardless of their length, although if desired the short words like "one," "two," "six" and "ten" may occupy a shorter space and have a spacing character 9 as shown in Fig. 7 to fill out the 70 full width of face. The use of wheels of similar construction not only results in 75 cheaper manufacture but enables amounts to be set up by choosing one word on each wheel. However, it is not intended to limit the invention to making the wheels similar or of equal width face or to making each word extend the full width of the face as 80 more than one word can be arranged in a line across the face of a wheel.

The type rows are arranged on the type wheels with their base lines parallel with the axis of the shaft 2, and the letters of the words are preferably of gradually decreasing size, the last letter being about half the height of the first, so that lines bounding the upper and lower ends of the letters gradually converge as shown in Fig. 7. As the type wheels are arranged in contact, 10 there is no spacing between a word on one wheel and a word in alignment therewith on an adjacent wheel; consequently the construction of the type with letters of graduated height is provided for the purpose of 15 rendering the printed line readily legible. In addition and as a result of this arrangement, a space is provided between the small ends of adjacent words, which is taken advantage of for driving the type wheels by 20 means of idlers 10, a set of which are mounted loosely on a shaft 11, extending across the casing. The idlers 10 are driven by gear teeth on indicating wheels 12 which, together with the corresponding type wheels, are independently shifted by rack bars 13, provided 25 with thumb pieces 14. The indicating wheels 12 have, on their peripheries, the same words arranged in the same order as on the corresponding type wheels, and these 30 words are visible through a slot 15 in the casing, the words appearing through the slot being the same as the type rows which are in printing position.

After the type wheels have been properly 35 positioned, an inking pad 16 carried by a swinging shield 17 is moved in contact with the type by means of a slight movement of the platen levers 6, this movement being brought about by cams 18 on the operating 40 shaft 19 which is revolved by a crank 20. The platen levers are then lowered, and the shield 17 swung out of the way by means of pivoted arms 21, and pitmen 22, actuated by cams 23 on the shaft 19. Continued 45 movement of the cams 18 then raises the platen levers their full stroke, carrying the paper into contact with the type wheel and impressing the line of words thereon.

In the normal operation of the machine, 50 the manually operable setting member which controls the selection of the type words on the extreme left hand type wheel is shifted until an index portion thereof registers with the appropriate character on the top of the 55 casing, when the word appearing through the slot 15 will indicate that the same word on the type wheel is in printing position. The succeeding words of the amount are then set up in the same manner on the adjacent 60 wheels.

A marginal stop 25 on the check table 26, which is carried by the platen lever 6, is engaged by the left end of the check positioning the latter beneath the type wheels so 65 that the words on the left wheel begin at a

point very close to the end of the check. Consequently the printed line begins so close to the left end of the check that there is no possibility of inserting a word or words before the line for the purpose of raising the 70 amount. Stops 27 adjustable in slots 28 in the plate 26 toward and from the platen determine the location of the printed line with reference to a longitudinal edge of the 75 check.

A blank space 24 may be provided on each type wheel in case the words appearing in the amount are less in number than the total number of type wheels, and the setting members for the remaining wheels not used are 80 left in the normal or idle position shown in Fig. 1, when the blank spaces 24 on the wheels will be opposite the platen and consequently no impression will be made from these wheels. If desired, a row of stars or 85 other arbitrary filling characters may be substituted on each type wheel in place of the blank spaces, so that a row of limiting characters would appear after the words in 90 the line.

Although the type rows have been shown as arranged on the periphery of a wheel, it is obviously immaterial to the invention whether the type carrying surface is curved or straight and the term "type carrier" is 95 intended to include any arrangement by which a group of separate word type forms of the construction previously described are arranged in a series, and means provided for selectively moving the group to bring any 100 one type form to printing position.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the 105 claims which follow.

What is claimed is:

1. A printing machine embodying a set of type carriers each having on its face a plurality of words extending the full width of the carrier, the words consisting of letters of 115 graduated height.

2. A printing machine embodying a set of type carriers each having on its face a plurality of words extending the full width of the carrier, each word consisting of letters which are graduated in height in one direction from the first to the last letter. 120

3. A printing machine embodying a set of type carriers each having on its face a plurality of words of equal length, the words 125 consisting of letters decreasing in height from beginning to end.

4. A printing machine embodying a set of type wheels each having on its periphery a plurality of words of equal length, the words 130

consisting of letters decreasing in height from beginning to end, and the base lines of the words being arranged parallel with the axis of the wheel.

5 5. A printing machine embodying a set of type carriers each having on its face a plurality of words, each consisting of letters which decrease in height from the beginning to the end of the word.

10 6. A printing machine embodying a set of cylindrical type wheels each having on its periphery a plurality of word lines of equal length, regardless of the number of letters in the lines, the spaces between the 15 word lines being greater at one side of the wheel than at the other.

7. A printing machine embodying a series of type carriers each having on its face a plurality of word lines of equal length regardless of the number of letters in the different lines, the spaces between the word 20 lines being greater at one side of the carrier than at the other.

8. In a printing machine, a set of independently adjustable type carriers each provided with a line of type for each of the various words employed in writing amounts, the type in each line being formed and spaced apart to make the lines all substantially the same in length regardless of the 30 number of letters in the line and graduated in height from one end of the line to the other, and means for independently adjusting the type carriers to set up various amounts.

9. In a printing machine, a set of independently rotatable type wheels each having on its periphery a line of type for each of the various words employed in writing amounts, 40 the type in each line being formed and spaced apart to make the lines all substantially the same in length regardless of the number of letters in the line and graduated in height from the beginning to the end of 45 the line, and devices for independently ro-

tating the type wheels to set up desired amounts.

10. In a printing machine, a series of adjustable type supports each carrying all of the word type used in printing money values, a fixed marginal stop to be engaged by the left hand edge of the work sheet, and means for successively adjusting the type supports beginning with the left hand support to position type to print complete amounts in a line, invariably beginning at a fixed point near the left hand margin of the work.

11. In a printing machine, a series of adjustable type wheels mounted with their sides in contact and each having on its printing face a word type form for printing each of the words used in expressing monetary values, the letters in each form being constructed and spaced apart to make all of the forms extend the full width of the printing face regardless of the number of letters in the word and having said letters uniformly decreasing in height from the beginning to the end of the form, and devices for adjusting the type wheels to set up various amounts ready for printing.

12. In a machine of the class described, the combination of a type carrier having on its face a separate type form for each of the words which the machine is constructed to print, each of said forms comprising a group of letters graduated in height from one end of the form toward the other, and means for taking impressions selectively from said forms.

13. In a machine of the class described, the combination of a type carrier having on its printing face a plurality of word type forms, each form extending the full width of the carrier and having the letters of the words graduated in height from one end of the form to the other, and means for taking impressions selectively from said forms.

CHARLES G. TIEFEL.
